HENRY B. FOULDER, OF GLENBROOK, CONNECTICUT, ASSIGNOR TO J. P. CURRY MFG. CO., INC., OF STAMFORD, CONNECTICUT, A CORPORATION OF NEW YORK.

MACHINE FOR TYING WIRE TIES.

Application filed February 7, 1924. Serial No. 691,124.

This invention relates to machines for tying wire ties, and more particularly relates to power driven bench tools for twisting wire ties about the necks of bags, the tools being adapted to be started at the will of the operator to automatically give a tie a predetermined number of twists and then to release it from the machine, automatically stopping in proper position to receive and to operate upon another tie.

The principal object of my invention is to provide a machine of the character described, and one which operates positively, rapidly, efficiently and smoothly, and requires little power; one which may be built small and light enough to be conveniently portable, comprising sturdy parts compactly assembled, and including a minimum number of delicate parts, such as would be apt to break or become displaced under rough or continued use. Another object of my invention is to provide a tool of the character described, and one in which the parts are so connected that synchronism of movement of all parts of the machine is assured at all times, and the parts are prevented from becoming out of adjustment. Another object of my invention is to provide a machine of the character described provided with starting mechanism which requires a positive motion on the part of the operator to start the machine each time to twist a tie, and is not effective to prevent the automatic stopping of the machine after it has completed each full cycle of movements. Another object of my invention is to provide a releasing tie holding head which is simple in construction and efficient in operation. Other objects will be in part obvious and in part pointed out herein-after.

This invention accordingly consists in the features of construction, combination of elements and arrangement of parts which will be exemplified in the construction hereinafter set forth and the scope of the application of which will be indicated in the following claims.

In order that a clearer understanding of my invention may be had, attention is hereby directed to the accompanying drawings forming a part of this application and illustrating one possible embodiment of my in-

vention. Referring to the drawings, Fig. 1 is a side elevation of a machine embodying my invention; Fig. 2 is a top elevation of the same; Fig. 3 is a sectional view of a portion thereof and is taken on the line 3-3 of Fig. 1, looking in the direction of the arrows; Fig. 4 is a sectional view of a portion thereof and is taken on the line 4-4 of Fig. 1, looking in the direction of the arrows; Fig. 5 is a side elevation of the twisting head and spindle in tie retaining condition, the twisting head and a portion of the spindle being shown in section; Fig. 6 is a view similar to Fig. 5, but shows the parts in tie releasing condition; and Fig. 7 is a view of a modified form of twisting head, a portion thereof being shown in section. Similar reference characters refer to similar parts throughout the several views of the drawings.

Referring to the drawings, the machine comprises a suitable base plate 1 having suitable spaced supporting standards 2 and 3. A drive shaft 4 is rotatably and slidably mounted on the standards. A pulley 5 is mounted on shaft 4 for constant rotation from a source of power (not shown). A clutch disc 6 is affixed by pin 6' to the shaft 4 on one side of pulley 5, and at the other side of the pulley 5 is a complementary clutch disc 7, which has a hub 8 rotatably extending through standard 2 and has a collar 9 secured to this hub on the opposite side of the standard. Shaft 4 rotates and slides in hub 8. A coil spring 10 is confined between the collar 9 and another collar 11 secured to the shaft 4, and this spring constantly urges the shaft 4 and its clutch disc 6 to move toward the front of the machine and to cause the pulley 5 to be clutched between the discs 6 and 7, so that the shaft 4 will rotate with the pulley 5.

A tie twisting spindle 12 is mounted for rotation in the standards 2 and 3, and preferably above and to one side of the shaft 4. This spindle carries a tie twisting head 13 at its forward end. The twisting spindle 12 is caused to be rotated whenever shaft 4 rotates through the intervention of a gear 14 secured to the shaft 4 and in constant mesh with a gear wheel 15, which is mounted for rotation on a stud 16 projecting from the standard 3. This gear wheel 15 carries a

crank arm 17 which reciprocates a sector gear element 18, the teeth of which are in constant mesh with a gear 19 fixed upon the twisting spindle 12. Sector gear 18 is mounted for rotatable reciprocation on a shaft 20 supported by the standards. It will be readily apparent that each time the gear wheel 15 makes one revolution, the spindle 12 will be rotated a certain number of turns in one direction and then will be rotated the same number of turns in the reverse direction into initial position. Preferably, the gear ratio is such that for each revolution of the gear wheel 15, the spindle 12 will be rotated two and one-half revolutions first in one direction and then in the reverse direction.

I provide means whereby the operator may quickly and easily throw in the clutch 6, 7 to cause the spindle 12 to undergo these rotations, and I also provide means whereby, when the spindle 12 has been rotated in one direction and then in the other into initial position, the clutch will be thrown out and the rotation of the drive shaft 4 will be stopped. I also provide means for releasing a twisted tie from association with the twisting head when the spindle has finished its rotation in tie twisting direction and as it starts rotation in the reverse direction.

21 is a finger or projection affixed to the shaft 4. 22 is a sleeve rotatably mounted on a stud 23 attached to the standard 3. To one end of this sleeve 22 is a finger portion 24, the front end 25 of which has a beveled surface 35 adapted to be moved into and out of the path of rotation of the finger 21, so that whenever the finger portion 21 rides up the beveled surface 25, the finger 21 and the shaft 4 attached thereto will be cammed rearwardly 40 and the clutch members 6, 7 will be opened and the shaft 4 will be disconnected from rotation from pulley 5 until the finger 25 is raised from behind the finger 21, and allows the clutch to be thrown in by the action of the spring 10. 26 is a shoulder on finger 24 behind tapered surface 25 against which the finger 21 strikes to stop rotation of shaft 4. 27 is a heel portion of finger 24 which is adapted to be releasably engaged in a notch 50 of a latch 28, which is pivotally mounted, as at 29, to a member 30, which in turn is pivotally mounted on the standard 3, as at 31, and is fixedly connected with a lever arm 32, which extends outwardly at the side of the machine, and, if desired, may be connected with a foot lever 33 by means of pivoted connecting link 34. 35 is a heel portion of latch 28 and 36 is a stop pin positioned to engage the portion 35 and thereby cam the latch 28 downward and out of engagement with the heel 27 of the finger 24, after the latch 28 has been moved inwardly, as a result of the lever 32 being moved downwardly, a sufficient distance to raise the finger 24 out of the path 60 of the projection 21. 37 is a spring attached

to latch 28 and to a pin 38 on standard 3, constantly urging latch 28 to assume engaging position with the heel 27 of finger 24. 39 is a spring connected with the lever 32 and with a stud or screw 40 secured to the standard 3, and which constantly urges lever 32 into raised position to place the latch 28 in position to engage the heel 27 of the finger 24. 70

Fixed to the other end of sleeve 22 is an arm 41, the end 42 of which constantly rides on the peripheral cam surface 43 of a cam disc 44 which is fixed to the gear wheel 15 for rotation therewith. The coaction between the cam disc 44 and the finger 41 is such that when the finger 41 rides on the raised surface of the cam, the finger 24 will be held out of the path of rotation of the drive shaft projection 21, but when the finger 41 rides on the depressed portion 45 of the cam disc 44, the finger 24 will be positioned in the path of 80 rotation of the projection 21. A spring 46 constantly urges the finger 24 to assume lowered position. 85

In one form of twisting head illustrated, there is pivoted to the body of the head a tie 90 engaging finger 50 having a heel portion 51 engaged by an end of a rod or pin 52 which is slidably mounted in the head, and which at its rear end is pivotally connected to one end of a link 53. This link is pivoted intermediate its ends, as at 54, to the twisting head, and at its other end, as at 55, is connected with the forward end of a rod 56 which extends rearwardly therefrom through the forward part of the spindle 12, and at its rear end carries a disc like member 57 which may be keyed to the rod 56, as at 58. At the location of this key the spindle 12 is slotted, as at 59, to permit longitudinal movement of the rod 56 and disc 57 with respect to the 100 spindle 12. As will be readily apparent, when the disc member 57 is in forward position, the rod 56 will be in forward position, the pin 52 will be in retracted position, and the finger 50 will be tilted forwardly to release a tie, all as shown in Fig. 6. When the disc 57 is in retracted position, the rod 56 will be in retracted position, the rod 52 will be in forward position, and the tie engaging 110 finger 50 will be locked in rearward tilting position to retain a tie thereon for and during twisting thereof. 115

60 is a lever pivoted at its lower end to a bracket 61 secured to the base 1 of the machine. The upper end 62 of this lever rests against the rear of the disc 57. Intermediate its ends, lever 60 has a riding surface 63, constantly in the path of rotation of a cam 64 formed on the rear surface of the cam disc 44, which is mounted for rotation with the gear 15. The arrangement is such that whenever the cam 64 actuates the lever 60, the disc 57 will be moved forwardly and the twisting head will be placed in tie releasing condition, but at other times a spring 65 associated with 120

125

130

the rod 52 of the twisting head constantly holds the twisting head in tie retaining condition.

From the above description and the drawings the operation of the machine will be readily apparent. In normal condition, the clutch members 6 and 7 will be open, the pulley 5 will be rotating freely on the shaft 4, and the twisting head will be in tie retaining position with the tie engaging finger extending upwardly in convenient position to receive and engage the ends of a tie. In tying a bag or the like, the operator, after he has passed a tie about the neck of the bag, engages the ends of the tie 100 with the finger 50. The operator then depresses the treadle 33, whereupon finger 24 will be raised behind the finger 21 of shaft 4, the clutch 6, 7 will become closed upon the pulley 5, and the rotation of shaft 4 starts, causing simultaneous rotation of gear wheel 15 and movement of sector gear 18 to rotate twisting spindle 12 in tie twisting position. As these movements start, the raised surface 43 of cam 44 will ride beneath the cam finger 41 to keep the finger 24 temporarily in raised position. When gear 15 has completed a one-half revolution, sector gear 18 has completed its movement in tie twisting direction, and at this time or immediately thereafter, cam 64 engages and actuates the lever 60 to move its upper end forwardly, and thus adjusts the twisting head into tie releasing condition. Preferably, when the tie twisting movement of spindle 12 is completed, the tie engaging finger 50 is found to extend downwardly, thus enhancing the ready and practically automatic release of the tie ends from the twisting head. As the gear 15 completes the last half of its single revolution, the sector gear is reciprocated for its full stroke in a reverse direction, thus restoring the twisting head into appropriate tie receiving position with the engaging finger 50 presented upwardly. Meanwhile, cam 64 has rotated out of engagement with the lever 60, thus permitting the twisting head to restore itself into proper condition for holding and twisting another tie. As the gear 15 approaches the end of its complete revolution, the depressed portion 45 of the cam disc 44 rides under the cam finger 41, thus allowing the finger 24 to be depressed by the action of the spring 46 into the path of rotation of the finger 21 on the shaft 4. The parts are so synchronized that when the gear 15 has completed its full revolution, the finger 21 will have ridden over the tapered surface 25 and against the shoulder 26 of the finger 24, and in consequence the clutch 6, 7 will be opened and the shaft 4 stopped. If the operator has released the treadle 33, allowing the lever 32 to raise, the latch 28 will now be in such engagement with the heel 27 of the finger 24 as to permit the operator to start the machine for another cycle of movements by merely depressing the treadle. However,

if the operator has maintained the treadle 33 depressed, the latch 28 will be out of engagement with the heel 27, and the machine will stop anyhow at the end of its cycle of movements and will not start again until the operator first allows the treadle 33 to raise and then depresses it. The treadle may be eliminated and the machine may be started by simply depressing lever 32 by hand. 70

The twisting head above described is suited for use with wire ties having looped ends, the loops being adapted to be engaged on the finger. Another form of head, and one which is suitable for use with wire ties, 101, having stub or knotted ends, 102, may comprise a 75 finger 103 at the front of the head and two pivotally mounted jaw members 104, 105, having at their front ends tie engaging seats 106 and 107, which are movable toward and from the finger 103 from opposite sides. When the seats 106, 107 are close to the finger 103, they form therewith grooves through which the tie ends extend, but through which the enlarged heads of the tie, which are behind the grooves, may not pass. When the seats 106 and 107 are away from the finger 103, the slots are large enough to permit the heads at the tie ends to pass therethrough, thus releasing the tie. 108 is a rod longitudinally movable in the head, and at its front end has a 80 boss or cam 109, which coacts with heel portions 110 and 111 of the jaws 104 and 105 in such a way that when the rod 108 is in forward position, the jaws 104 and 105 are free to open to release a tie, and when the rod 108 is in retracted position, the jaws 104 and 105 are locked in tie retaining position. A spring 112 is so associated with the rod 108 as to continually urge this rod to assume retracted position. This type of twisting head may 85 be substituted in the machine above described for the head 13, the rod 108 taking the place of the rod 56 of the head described heretofore. 90

As many changes could be made in the above construction and as many apparently 110 widely different embodiments of this invention could be made without departing from the scope thereof, it is intended that all matter contained in the above description or shown in the accompanying drawings shall 115 be interpreted as illustrative and not in a limiting sense.

What I claim is:—

1. In an apparatus of the character described, in combination, a twisting head including a pivoted tie engaging member, a pin slidable on said head and engaging said member for placing said member in and out of tie retaining position, a rod slidably mounted in said head and a pivoted link connecting said rod and said slidable pin, and means for adjusting said rod forwardly and rearwardly in said head to pivot said tie engaging member into tie retaining and tie releasing positions. 120

2. In a device of the character described, a rotatable head having a prong adapted to penetrate the loops of loop end wire ties and pivotally movable on the head into a rearwardly inclined tie engaging and retaining position and into a forwardly inclined tie releasing position.

3. In a device of the character described, a rotatable head having a prong adapted to penetrate the loops of loop end wire ties and pivotally movable on the head into a rearwardly inclined tie engaging and retaining position and into a forwardly inclined tie releasing position, and means normally holding the prong in the rearwardly inclined tie retaining position.

4. In a device of the character described, a rotatable head having a prong adapted to engage in the loops of loop end wire ties and pivotally movable on the head into rearwardly inclined tie retaining position and into forwardly inclined tie releasing position, means normally holding the prong in the rearwardly inclined tie retaining position, and means for moving said prong into said forwardly inclined tie releasing position.

5. In an apparatus of the character described, in combination, a twisting head including a pivoted prong engageable in the loops of loop end ties, a twisting spindle associated with said head, means including an oscillating member for periodically rotating the spindle a predetermined number of turns first in one direction and then in the reverse direction, and means for maintaining the prong in a rearwardly inclined tie retaining position during rotation of the spindle in one direction and for then moving the prong into a forwardly inclined tie releasing position.

6. In an apparatus of the character described, in combination, a twisting head including a pivoted prong engageable in the loops of loop end ties, a twisting spindle associated with said head, means including an oscillating member for periodically rotating the spindle a predetermined number of turns first in one direction and then in the reverse direction, and means for maintaining the prong in a rearwardly inclined tie retaining position during rotation of the spindle in one direction and for then moving the prong into a forwardly inclined tie releasing position,

said oscillating member rotating said spindle two and one-half turns in each of said directions.

7. In an apparatus of the character described, in combination, a twisting head including a pivoted prong engageable in the loops of loop end ties, a twisting spindle associated with said head, means including an oscillating member for periodically rotating the spindle a predetermined number of turns first in one direction and then in the reverse direction, means for maintaining the prong in a rearwardly inclined tie retaining position during rotation of the spindle in one direction and for then moving the prong into a forwardly inclined tie releasing position, and an actuator for driving said oscillating member and for operating said last-mentioned means.

8. In an apparatus of the character described, in combination, a twisting head including a pivoted tie engaging prong, a pin slidable on said head and engaging said prong for placing said prong in and out of tie retaining position, a rod slidably mounted in said head and a pivoted link connecting said rod and said slidable pin, a gear on said spindle, a toothed member in mesh with said gear, an actuator for oscillating said toothed member to rotate said spindle back and forth, and a connection between said actuator and said rod whereby said rod is adjusted to maintain said prong in tie retaining position during rotation of the spindle in one direction and then the rod is retracted to place the prong in tie releasing position.

9. In an apparatus of the character described, in combination, a twisting spindle including a tie-holding head adjustable into and adjustable out of tie-holding condition, means, including an oscillating sector gear for rotating the spindle and head in alternate directions, means, including a rotating cam, for maintaining the head adjusted in tie-holding condition during tie-twisting rotation of the spindle, and for then adjusting the head into tie-releasing condition, and means for driving said oscillating sector gear and cam in synchronism.

This specification signed this 5th day of February, 1924.

HENRY B. FOULDER.
